(21) Appl. No.: **29/134,750**

(57) **CLAIM**

(22) Filed: **Dec. 29, 2000**

The ornamental design for a combined vehicle alarm trans-
mitter/pager and key ring, as shown and described.

(51) LOC (7) Cl. **10-05**

DESCRIPTION

(52) U.S. Cl. **D10/106**

FIG. 1 is a front elevational view of the combined vehicle
alarm transmitter/pager and key ring of the present invention;

(58) Field of Search **D10/104, 106,**

FIG. 2 is a rear elevational view of the combined vehicle
alarm transmitter/pager and key ring of FIG. 1;

**D10/116, 121; 340/540, 541, 545, 565,
568, 571, 572, 573, 584**

FIG. 3 is a left side elevational view of the combined vehicle
alarm transmitter/pager and key ring of FIG. 1, the right
view being a mirror image thereof;

FIG. 4 is a top plan view of the combined vehicle alarm
transmitter/pager and key ring of FIG. 1; and,

FIG. 5 is a bottom plan view of the combined vehicle alarm
transmitter/pager and key ring of FIG. 1.
